UNITED STATES PATENT OFFICE.

JONATHAN WRIGHT AND WILLIAM H. MARSHALL, OF PLEASANTVILLE, NEW YORK.

METHOD OF DIFFUSING WATER-VAPOR IN THE ATMOSPHERE OF ROOMS.

1,285,879.

Specification of Letters Patent. Patented Nov. 26, 1918.

Application filed February 10, 1916. Serial No. 77,426.

To all whom it may concern:

Be it known that we, JONATHAN WRIGHT and WILLIAM H. MARSHALL, both citizens of the United States of America, and both residents of Pleasantville, Westchester county, New York, have invented certain new and useful Improvements in Methods of Diffusing Water-Vapor in the Atmosphere of Rooms, of which the following is a specification.

Our invention consists in a method of diffusing water vapor in the atmosphere of a room so as to secure and maintain the proper relationship between the temperature of the room in cold weather and the humidity. The purpose of the invention is accomplished by means of the evaporation of water, the expansion of the resulting water vapor and the diffusion of the same throughout the room by means of currents of hot air.

In order to fully explain the results arrived at it will be necessary to first set forth the theoretical and practical principles involved.

The free air surrounding dwellings contains water vapor in proportion to the temperature and varying to a considerable degree with other factors not necessary to enumerate. The relationship of temperature and water-vapor-content of the air is expressed by the "dew point," defined as "that temperature of the air at which the moisture present in it just saturates it." In evaporating water in a room, the vapor must be rapidly removed from the point where it is generated or it will condense and be precipitated there, and thus its diffusion into the general atmosphere of the room prevented. As the temperature falls the saturation point of the air for water vapor is correspondingly lowered. Below the freezing point the water vapor content of the outdoor air becomes rapidly very small. Ordinarily this air is drawn into steam heated houses where the temperature is 70° F. or above. This high temperature and very low humidity, due to out-door freezing, quickly extract moisture from furniture, woodwork, books, etc. which are soon damaged thereby. More seriously, it results in rapid evaporation of moisture from the surface of human beings, causing a feeling of chilliness even at a high temperature of the surrounding air in the room. All living beings, plants as well as animals, are

surrounded by a thin layer of air filled by vapor from their own bodies, which being a bad conductor of heat, helps to preserve the body temperature within physiological limits. In the open air, exercise by producing bodily heat and increasing the insensible perspiration and thereby the density of the vapor filled layer around the body neutralizes the low temperature and low humidity of cold air, or the addition of clothing must be made to retain the vapor layer around the animal body and its heat.

Within a dwelling where exercise and excessive clothing are not practicable, the conditions of the air are such, when a low temperature, 0° F. for instance, exists outside, that rapid evaporation induces the chilliness of the body surface even when the temperature within the house registers 75° or 80° F. To obviate this condition, and to save the wastage of fuel, it is necessary to supply the air in the dwelling with a proper amount of moisture as this will prevent too rapid evaporation from the surface of the body. As a matter of fact this proper amount is very large, far in excess of what has hitherto been supposed necessary and far in excess of what is practicable to secure from the vapor within the ordinary steam heating system, for example, or from the evaporation of water in pans on, or in contact with, pipes and radiators, for while in warm, moist weather little or no extra evaporation is necessary and in fact may be undesirable, in dry zero weather an amount of water probably in excess of a gallon a day per 100 cubic feet of room space is not too much. This variation in evaporation, our method is able to accomplish under favorable conditions, the amount of vapor available increasing to a large extent automatically as the humidity of the air introduced from the outside falls. The problem rests fundamentally on the fact that you must not only generate water vapor as distinguished from steam, which condenses as soon as mingled with the colder air and is precipitated, but the vapor must be diffused through the room by superheating it, as by causing it to impinge against the hot coils or pipes of the radiator above the evaporating pan, and sent out through the room in the currents of hot air before it condenses and is precipitated. Simple generation of the water vapor is not enough.

It must be expanded by additional heat, supplied for example by the radiator.

- The general method by which we have secured this result consists in immersing the 5 lower part of some of the steam carrying coils of a steam radiator, for example, or a portion of the steam supply pipe of the radiator, in a receptacle of water, beneath the radiator. The vapor arising from the 10 contact of the water with these hot surfaces may be regulated in amount by the extent to which the water is allowed to cover these surfaces. As the vapor rises from beneath the radiator coils it is borne up between and 15 around them by the currents of hot air they generate and thrown out into the general atmosphere of the room, the heat from the radiator preventing condensation of the vapor.
- 20 No extra supply of fuel is necessary, in practising our method, to generate any given amount of heat. As a matter of fact a large saving of fuel is attained because it is not necessary to keep the temperature of 25 the living room (otherwise at 80° F.) above 70° F. in the coldest weather. Physical comfort and health is vastly greater at the latter temperature of properly moistened air than at one 10° higher, which under the 30 present conditions, without air moistening, it is necessary to obtain to be comfortable in the coldest weather.

In the following we have described, with reference to the accompanying drawings, a 35 means for practising our method, the features thereof being more particularly pointed out hereinafter in the claims.

In the drawings Figure 1 is a side elevation of one form of apparatus adapted for 40 the carrying out of our invention; Fig. 2 is an end elevation of the same.

Similar numerals of reference indicate similar parts throughout the several views.

In the drawings 1 indicates the usual 45 form of steam radiator formed of a plurality of sections 2, 2 suitably connected for the passage of steam therethrough. 3 (Fig. 1) indicates the steam supply pipe, provided with a shut-off valve 4 for controlling 50 the passage of steam from pipe 3 through pipe 5 into sections or coils 2, 2. 6 indicates the usual air valve. 7 indicates a receptacle for water placed beneath radiator 1 and open at the top. 8 indicates the water supply pipe controlled by float valve 9. The 55 float 10 of float valve 9 is provided with a relief valve 11 to permit the escape of air in the float upon becoming heated. 12 indicates an over flow pipe. 13 indicates a door, 60 preferably water tight permitting access to float valve 9 for purposes of regulation. 14, 14 indicate supports for legs 15, 15 of radiator 1.

The apparatus as described and as shown 65 in Figs. 1 and 2 is peculiarly adapted for use

in connection with existing heating systems. Steam supply pipe 3 is shown as extending diagonally upward through and across receptacle 7 from the lower or steam pipe entrance end to the upper or steam pipe exit end of the receptacle. The diagonal course of the pipe through the water in the receptacle permits the more accurate regulation of hot surface to be covered by the water, the relation between the surfaces 75 radiating dry heat through the air and surfaces for vaporizing water from the receptacle being varied by covering more or less of the hot pipe in the receptacle with water. The method of varying or regulating the 80 amount of pipe surface covered by the water is obvious. For example the overflow pipe may be capable of vertical or telescopic adjustment in the usual well known way. The distance between the surface of the water and the bottom of the heating means 85 may thus be maintained at any predetermined point. The depth of the water in the receptacle is immaterial provided the requisite surface of hot pipe is covered, but 90 the amount of vapor generated is to a large degree dependent upon the area of water surface exposed.

The water vapor rising from the receptacle passes upward against and around the 95 sections or coils of the radiator, as indicated by the arrows, and is there superheated and expanded, the temperature of the radiator being higher than the temperature of the water vapor. The rising current of warm 100 air from the radiator will diffuse the superheated and expanded water vapor out into the room laterally of the radiator (assuming the latter to be adjacent a wall) as indicated by the arrows in Fig. 2. It is essential that the water vapor impinge against no surface or mingle with no air colder than itself before it is expanded or diffused as otherwise it will condense and precipitate.

The inflow of water to the receptacle may 110 be adjusted by means of the valve 9 so that just the amount of water vapor will be given off to furnish the atmosphere of the room with the desired percentage of moisture at the temperature of the room.

While we have described the method in connection with a steam heating system it is obvious that it is not restricted to use in connection with such. It may readily and obviously be used in connection with hot water heating systems and the principles of the invention are applicable to other heating systems as well.

The method however possesses especial 125 advantages in connection with steam heating systems. It avoids the abstraction of heat from the steam pipes and the condensation or "killing" of the steam within them, by regulating the water in the receptacles so that just the quantity of water is let into 130

the receptacle which the hot pipe and coil surfaces vaporize. The water gages show the height of the water on these surfaces which can be regulated according to the desire of the inmates for more or less moistening of the atmosphere.

This method of air moistening may be applied to each radiator or steam pipe or to one or more, as desirable, in a private dwelling or larger building. The interference with the free circulation of the vapor, arising from the water receptacle among the hot steam or water coils above, by means of which it is further heated and expanded, has prevented some of the previous devices from working. This, properly provided for by the close approximation of the water coils to the water yet allowing a free draft and circulation of air from below upward in currents generated by the steam or hot water pipes, obviates any necessity for a fan, contact with the blades of which or with any surface cooler than the vapor tends immediately to condense it into water and prevents its further circulation. A revolving fan used for this purpose, unless made hotter than the water vapor would disperse the air, but not the vapor of the water. Indeed it would tend more quickly to condense the latter, by making air currents independent of those generated by heat.

As an example of the quantity of water necessary for the proper moistening of the air of a room we might state that in the use of one form of our apparatus in a room of approximately 2800 cubic feet we evaporated over a period of some weeks an amount of water sufficient to produce at 70° F. of the dry bulb of the hygrometer a position of the mercury in the wet bulb of about 60° F. representing a humidity of 56 per cent., while in a room in which dry radiation alone existed the humidity was at the same time approximately 30%, these being the readings of the instruments in the rooms when the temperature outside the house was about 20° F. The amount of water evaporated to produce this result was approximately a gallon an hour and with a lower outside temperature and consequent lower degree of humidity would even exceed this amount. Any device or method which would not provide for a very wide variation in moisture evaporated would therefore be inefficient. Furthermore by the practice of our method we are enabled to decrease the amount of

radiating surface of the heaters by an amount approximately 20% and upward.

We claim:

1. A method of diffusing water vapor in the atmosphere of a room consisting in providing an open topped receptacle for water in close proximity to but beneath a steam radiator, heating the water to evaporate the same by passing the steam supply pipe inclined through the water receptacle to the radiator so that the water is subjected to the heat from the pipe before the steam reaches the radiator, maintaining a constant predetermined relation between the height of the water in the receptacle and the amount of the surface of the steam supply pipe covered thereby while permitting regulation of said height, maintaining the radiator at a temperature above the temperature of the water vapor from the receptacle, passing the water vapor upward from the exposed surface of said receptacle in an unobstructed path directly to and around said radiator, expanding said water vapor by contact with the surfaces of said radiator and bringing the expanded vapor in the path of a current of hot air within and around said radiator to diffuse the same through the room.

2. A method of diffusing water vapor in the atmosphere of a room consisting in providing an open topped receptacle for water in close proximity to but beneath a heating means, heating the water to evaporate the same by subjecting it to the influence of heat radiated from the medium for heating the heating means before said medium reaches said heating means, regulating the amount of water vapor given off by maintaining a constant predetermined relation between the height of the water in the receptacle and the surface transmitting said radiated heat while permitting regulation of said height, maintaining said heating means at a temperature above the temperature of the water vapor, passing said water vapor upward from the exposed surface of said receptacle in an unobstructed path to and over said heating means, superheating and expanding said water vapor by contact with said heating means and bringing the superheated and expanded vapor in the path of a current of hot air to diffuse the same through the room.

In testimony whereof we have signed this specification.

JONATHAN WRIGHT.
WILLIAM H. MARSHALL.
